(57) **CLAIM**

The ornamental design for a collision damage pointer device,
as shown and described.

DESCRIPTION

FIG. 1 is an elevation view of my new design of a collision
damage pointer with the telescoping segments shown in an
unextended position.

FIG. 2 is a top view of the collision damage pointer shown in
FIG. 1. In this view the pointer arrow is lined for the color
orange.

FIG. 3 is a bottom view of the collision damage pointer shown
in FIG. 1. In this view the pointer arrow is lined for the color
red.

FIG. 4 is a left side view of the collision damage pointer
shown in FIG. 1; and,

FIG. 5 is a right side view of the collision damage pointer
shown in FIG. 1.
